UNITED STATES PATENT OFFICE.

JOHN L. KOCHENDERFER, OF SEWICKLEY, PENNSYLVANIA, ASSIGNOR TO MERGEN-THALER LINOTYPE COMPANY, A CORPORATION OF NEW YORK.

TYPE OR MATRICES.

1,101,290.

Specification of Letters Patent. Patented June 23, 1914.

Application filed July 5, 1913. Serial No. 777,569.

To all whom it may concern:

Be it known that I, JOHN L. KOCHENDERFER, a citizen of the United States, residing at Sewickley, in the county of Allegheny and State of Pennsylvania, have invented certain new and useful Improvements in Type or Matrices, of which the following is a specification, reference being had therein to the accompanying drawing.

10 This invention relates to linotype machines of the general construction represented in Letters Patent of the United States to Ottmar Mergenthaler No. 436,532 wherein circulating matrices bearing formative type characters are stored in a magazine and released therefrom by the manipulation of finger keys, the matrices assembled in line in the order in which the type are to appear in print, the assembled line justified and presented to a slotted mold into which molten metal is injected, which solidifying against the formative characters will form a printing bar or slug, bearing on its edge, type characters corresponding 20 to the characters of the matrix line. After the casting operation, the matrix line is transferred to a matrix distributing mechanism, by which the matrices are automatically restored to the magazine from which 30 they started.

More particularly the invention has reference to a special form of matrix, designed for the production of so-called "encircled figures," that is, numerals inclosed by a 35 surrounding line or border. At the present time, matrices are provided which bear such encircled figures or numerals, a separate matrix being required for each numeral or combination of them. Inasmuch 40 as for certain classes of work, whole numbers are employed comprising various combinations of numerals, if a separate matrix is used for each number, it will be necessary to employ a greater number of matrices 45 than can be conveniently handled in the machine to provide for all the different combinations. I propose in accordance with my invention, to provide for the production 50 of numbers consisting of all combinations of numerals, while employing a minimum number or assortment of matrices, and this I accomplish by employing a composite or built-up matrix consisting of a plurality of complementary sections or members, each 55 bearing a portion of the whole number and

a portion of its inclosing line or border, the arrangement being such that by employing the matrix sections interchangeably in different combinations, whole numbers of different numerical values, and made up of 60 different numbers of individual numerals, may be produced.

My invention is susceptible of embodiment in many different forms and constructions, that shown being merely by way of example. Therefore it will be understood that the invention is not limited to any particular form or construction of the parts except in so far as such limitations are specified in the claims. Further it will be 65 manifest that my invention is not limited in its use and application to linotype machines of the character outlined, but may be employed in connection with other types of machines for producing type lines or 70 type bars, and in connection with type casting, type setting and like machines.

Figure 1 is a plan view of a series of matrix sections provided with different numerals and each having one end portion of 80 an inclosing line; Fig. 2 is a similar view of a series of matrix sections adapted to be used in combination with the others, provided with different numerals, and with the intermediate portions of the inclosing line; 85 Fig. 3 is a similar view of a series of matrices for use in combination with the others, and provided with different numerals and with the other end portion of the inclosing line; Fig. 4 is a perspective view 90 of a number of the matrix sections of the form shown in the preceding figures, assembled as a composite matrix, to produce a number consisting of four numerals, with an inclosing line or border; Fig. 5 is a 95 similar view of a composite matrix made up of three sections to produce a number containing three numerals, and a surrounding line or border; Fig. 6 is a similar view of a composite matrix made up of sections 100 of the form of Figs. 1 and 3 to produce a number containing two numerals with an encircling line.

Referring to the drawings: A set or series of matrix sections A—A, etc., is represented in Fig. 1, each matrix being provided with a formative numeral character *a*, from 0 and 9 on the respective sections. Associated with the numeral character of each section, is one semi-circular end por- 110

tion a' of a formative inclosing line or border, which inclosing line on the composite or built-up matrix as represented in Figs. 4, 5 and 6 incloses the whole number represented by the said matrix. A series or set of matrix sections B—B, etc., is represented in Fig. 3, each provided with a formative numeral character b , from 0 to 9 on the perspective sections, which numerals have associated with them the other semi-circular end portion b' of the said inclosing line. In Fig. 2 is represented a series or set of matrix sections C, C, etc., each provided with a formative numeral character c , from 0 to 9 on the respective sections, with which are associated, the intermediate straight horizontal portions c' of the formative border line.

The matrix sections of one of the series or sets are interchangeable with those of the other sets, and they are adapted to be employed in combination with each other in building up different forms of composite matrices as represented for example in Figs. 4, 5 and 6, to produce different combinations of numerals, with an inclosing line or border; and the portions of the border lines are so located on the respective sections, that the ends of the lines on the sections of one set will join the ends of the lines on the sections of the other set, when said sections are assembled side by side, with the result that a practically continuous inclosing line will be produced on the composite or built-up matrix. In Fig. 4 for instance is represented a composite matrix made up of four matrix sections to produce a whole number consisting of four numerals, inclosed in an elliptical border line. In building up this matrix, matrix sections A and B bearing the end portions of the border line, are combined with two of the matrix sections C bearing the intermediate portions of the border line, the said sections being assembled side by side with the sections A, B on the ends, and the other sections between them.

In Fig. 5 a composite matrix is shown made up of three sections to produce a whole number consisting of three numerals, with an elliptical inclosing line. In this instance as in Fig. 4, the sections A and B are employed to produce the end portions of the inclosing line, and a single section C is assembled between the others to produce the intermediate portions of the line.

In Fig. 6 a composite matrix is shown made up of but two sections to produce a whole number consisting of two numerals. In this case, sections A and B only are employed and the inclosing line made up of the two semi-circular portions, is circular instead of elliptical.

From the foregoing description it will be manifest that any combination of numerals,

with a continuous inclosing line may be produced by the employment of the matrix sections of the different forms in combination, the sections of one set being adapted to be employed in various combinations with the sections of the other sets, and the sections of the intermediate set being adapted to be employed in combination with each other. As a result, the assortment or number of sections or matrices required will be reduced to a minimum, so that it will not be necessary to employ a greater number than can be conveniently and properly handled in the machine.

While I have shown the end portions of the inclosing line semi-circular, and the intermediate portions straight, to produce a circular inclosing line in the one case, and an elliptical or elongated inclosing line in the other case, it will be manifest that other forms of inclosing lines may be employed, either in the form of a continuous line, or a dotted line or a combination of dots and dashes, and the like. Further it will be understood that the matrix sections may be provided with letters or other figures, instead of numerals in the event of its being desirable to print a number of letters or characters surrounded by an inclosing line. And further it will be understood that the matrix sections may differ in form and shape from that shown, provided they are adapted to be used conjointly and interchangeably in the manner indicated.

Matrix sections of the form shown and described may be assembled and employed in the justified line with the usual and ordinary letter matrices, and they may be inserted and removed from the line by any appropriate and suitable means, or by hand; or they may be circulated in the machine with the other matrices, in which case they will be provided with a distributing combination D as shown by dotted lines in Figs. 4, 5 and 6 designed to coöperate with the well-known distributing bar or rail of the machine with which the usual and ordinary matrices coöperate.

Having thus described my invention what I claim is:

1. A series of matrix sections, each having a character thereon and one end portion of a common inclosing line, in combination with a second series of matrix sections, each having a character and the other end portion of the inclosing line, the sections of one series being adapted for use in various combinations with the sections of the other series, and the portions of the inclosing line being so disposed on the respective sections that they will form continuations of each other and constitute a complete inclosing line when the sections are assembled in operative relation to each other.

2. A series of matrix sections each having

a character thereon and one end portion of a common inclosing line, in combination with a second series of matrix sections each having a character thereon and the other 5 end portion of the common inclosing line, and a third series of matrix sections, each having a character thereon and the intermediate portion of the common inclosing line, the sections of the two first mentioned 10 series being adapted for use in various combinations with each other and with the sections of the third series, and the sections of the third series being adapted for use in various combinations with each other, the 15 portions of the inclosing lines being so disposed on the respective sections that they will form continuations of each other and constitute a complete inclosing line when the sections are assembled in operative relation to each other.

3. A set of matrix sections for producing different combinations of encircled numbers, said set comprising two series of matrix sections each series having the full complement 25 of digits, the sections of one of the series being provided each with one end portion of a common inclosing line, and the sections of the other series being provided each with the other end portion of the common inclosing line, the sections of one series 30 being adapted for use in various combinations with the sections of the other series, whereby various combinations of numbers

with a complete inclosing line may be produced by the association of the sections of 35 one series with the sections of the other series.

4. A set of matrix sections for producing different combinations of encircled numbers, said set comprising three series of matrix 40 sections, each series having the full complement of digits, the sections of one of the series being provided each with one end portion of a common inclosing line, the sections of another of the series being provided 45 each with the other end portion of the common inclosing line, and the sections of the third series being each provided with the intermediate portion of the common inclosing line, the sections of the two first mentioned 50 series being adapted for use in various combinations with each other and with the sections of the third series, and the sections of the third series being adapted for use in various combinations with each other, 55 whereby by the association of the sections of the different series, various combinations of numerals with a complete inclosing line may be produced.

In testimony whereof I have affixed my 60 signature in presence of two witnesses.

JOHN L. KOCHENDERFER.
